UNITED STATES PATENT OFFICE

2,480,194

ELECTRICAL APPARATUS

Carol G. Montgomery, Belmont, Mass., assignor,
by mesne assignments, to the United States of
America as represented by the Secretary of War

Application April 26, 1944, Serial No. 532,861

3 Claims. (Cl. 315—39)

1

This invention relates to an electrical apparatus and more particularly to a detachable holder for a gas discharge type switch. The switch involved comprises a cavity resonator wherein switch operation results from a change in electrical condition in the resonator. Such a change initiates a discharge across a gap therein which causes the resonator to become detuned, and consequently non-conducting. In this manner a circuit beyond the switch is electrically isolated from other parts of an associated system.

A switch of this character finds particular application in a radio-echo detection system wherein a transmitter and a receiver are located in close proximity to each other. In such a system it is customary to pulse a transmitter at fixed intervals and utilize received echo pulses for determination of target data. A detection system of this character may have separate transmitter and receiver antennae, or it may utilize a common antenna. Regardless of the type of antenna system used, the amount of power radiated from the antenna during transmitter operation is extremely large in comparison to the amount of power necessary and desirable for receiver operation. Thus there is a problem of protecting the receiver, particularly the crystal detectors therein, from excessive energy input during transmitter operation. The present switch functions to disconnect the receiver from the antenna during transmitter operation, and then re-establish the connection during the intervals between transmitter operation.

A protective switch of this character is shown and described but not claimed in the co-pending application of Harold K. Farr, Serial Number 488,098, filed May 22, 1943.

In the usual radio-echo detection system, very high radio frequencies generally are used. At these high frequencies, it is customary to use hollow wave guide type transmission lines. The present switch is adapted for use in such a hollow wave guide transmission system. In the following discussion it is assumed that a common antenna is used both for transmission and reception, although, of course, the invention would be applicable to a two or more antenna system.

The instant switch comprises a highly tuned cavity resonator disposed within and forming a part of the wave guide transmission line which connects the receiver to the antenna. The resonator is embodied in a gas-filled breakdown type discharge tube mounted in the wave guide. The tube has a direct current bias potential which maintains an electric field in the tube at a value

2

just below that at which conduction may take place. During transmitter operation, the high intensity energy pulse sufficiently increases the field so that a discharge occurs. As a result, the resonator is de-tuned for the operating frequency and the receiver is effectively disconnected from the system. At the conclusion of the pulse, conduction ceases, and the resonator again becomes tuned, whereby echo pulses received by the antenna may be communicated to the receiver.

The operation of the switch depends upon the fact that a gaseous discharge will occur at a predetermined, small potential above the direct current bias potential. The operating characteristic of any gas discharge device gradually changes with time due to a phenomenon, known as sputtering, which occurs at the tube electrodes. Sputtering, generally caused by positive ion bombardment, results in the deposit of metallic electrode particles on the tube walls. This is particularly harmful in the present instance wherein the tube constitutes a cavity resonator, because the resonant frequency thereof will change as metal is sputtered on the tube walls. Also, gas within the tube is occluded by the sputtered electrode particles with the result that in time, gas pressure decreases to a point where the tube becomes inoperative, or at least inoperative at the potentials used. Since failure of the tube to operate properly will result in a surge of high power into the receiver, considerable damage may result by reason of these changed operating characteristics. Therefore, it is necessary to provide a simple mechanical structure for the ready removal and replacement of such a gas tube. The principal object of the invention, therefore, is to provide such a structure.

In the drawing, Fig. 1 is a sectional view of the invention, Fig. 2 is a sectional view on the line 2—2 of Fig. 1, and Fig. 3 is a sectional exploded view showing details of the detachable tube mounting structure.

Referring now to Fig. 1, rectangular wave guide 5 extends between a transmitter and an antenna. A second rectangular wave guide 6 extends at right angles from guide 5 through a protective switch, generally indicated by 7, to a receiver. Guides 5 and 6 may be coupled together in any usual manner, a choke structure preferably being provided to avoid radiation losses. Thus wave guide 5 has rigidly fixed thereto a circular structure 8 having an annular channel 9 and a flange 10. The adjacent end of guide 6 has a cooperating circular flange 11, the outer portion thereof being secured to flange 10 by screws 12. Struc-

ture 8 has a rectangular central opening aligned with and forming a part of wave guide 6. There is a small clearance 13 between the main body of structure 8 and flange 11, clearance 13 extending between annular channel 9 and the space within the guide. Channel 9 is of proper depth to constitute a quarter wave choke to prevent radiation loss at the joint. A similar joint, generally indicated by 14, may be provided on the opposite side of switch 7.

Referring now to switch 7, wave guide 6 is provided with aligned circular openings in its opposing wide sides 15 and 16. An annular metallic sleeve 17 is snugly received in said circular openings, a portion 18 thereof being provided at the top to overlie side 15 around its opening. Sleeve 17 is rigidly fixed to guide 6, as for example by solder, to provide a good electrical connection therebetween. The inner surface 19 of sleeve 17 is tapered from a wide diameter at the top within portion 18 to a narrower diameter at the end associated with opposite side 16. Portion 18 has a shallow radial slot 20 adapted to receive an aligning pin carried by a later described member of the switch assembly.

A tube-carrying metallic sleeve 24 has its exterior surface tapered as shown at 25 for cooperation with the tapered interior surface of sleeve 17. Sleeve 24 is adapted to be received within sleeve 11, the tapered surfaces thereof cooperating to properly position sleeve 24 and associated tube within sleeve 17, and to provide good electrical contact therebetween. The interior cylindrical surface of sleeve 24 has two inwardly extending annular flanges 26 and 27, said flanges comprising supporting contacts for the later described gas discharge tube. Sleeve 24 extends somewhat beyond the ends of sleeve 17, the ends of sleeve 24 being threaded as shown at 28 and 29. Sleeve 24 is split as shown in the drawing so that the sleeve may be circumferentially expanded to receive the tube. A small circular aperture 29a (Fig. 3) is provided in sleeve 24, preferably at the split, for alignment with slot 20 in sleeve 17. If desired, sleeve 24 may be split in two places instead of one, registering means being provided on the two sections to permit accurate assembly.

Sleeves 17 and 24 have portions aligned with wave guide 6 cut away to provide transverse channels, generally indicated by 30 and 31, these channels constituting portions of wave guide communicating with the associated cavity resonator. The two sleeves have additional aligned portions cut away to provide opposed circular openings 32 and 33 (best shown in Figs. 2 and 3) which cooperate with means later described for tuning the resonator.

A gas-filled discharge tube 35 is carried within sleeve 24. Tube 35, well known in this art, includes two oppositely disposed horn-shaped electrodes 36 and 37, the narrow ends of the horns being spaced to provide a discharge gap 38 within glass tube envelope 39. The flaring ends of the horns extend through envelope 39 and terminate in annular flanges 40 and 41 which are received on flanges 26 and 27, respectively, of sleeve 24. As will be understood, sleeve 24 is expanded circumferentially at the slit to permit mounting of the tube within the sleeve. Tube 35 has a "keep-alive" electrode 42 terminating adjacent gap 38 within electrode 37, electrode 42 being connected through lead 43 to a suitable source of D. C. bias voltage. The oppositely disposed electrodes 36 and 37 cooperate to define an annular cavity resonator which, during the time the resonator

is in tuned condition, functions somewhat as a one-to-one transformer in wave guide 6. The resonator is positioned in guide 6 at a point generally a half wave length distance from the junction of guide 6 with guide 5. Thus, impedance conditions existing at the resonator will be reflected to the junction. When the resonator impedance is low (resonator is tuned) a low impedance exists at the junction to direct antenna energy to the receiver. Conversely, when resonator impedance is high (as occurs with a resonator de-tuning discharge during transmitter operation), a high impedance exists at the junction in the direction of guide 6 whereby little if any energy passes to the receiver.

Flange 41 of electrode 37 is maintained in position on supporting flange 27 by a retaining sleeve 45, which snugly telescopes sleeve 24 and bears on flange 41. A positioning pin 46 is carried by sleeve 45, pin 46 extending through aligning aperture 29a in sleeve 24 and being received in radial slot 20 of sleeve 17. Pin 46 provides for proper alignment of the various members of the assembly. Retaining sleeve 45 is reduced in section 25 at its end to provide a shoulder 47. A ring nut 50 is removably associated with threads 29 of sleeve 24, nut 50 having a bearing portion 51 adapted to engage shoulder 47 of sleeve 45. A somewhat similar structure is provided at the 30 opposite end of sleeve 24 wherein a second retaining sleeve 55 telescopes sleeve 24 and bears against flange 40 of electrode 36 to maintain said flange in position on supporting flange 26. In both instances, the electrode and supporting 35 flanges provide electrical as well as mechanical connections for the tube. An annular nut 56 is detachably associated with threads 28 at the lower end of sleeve 24, nut 56 being adapted to bear against the lower end of sleeve 17 to lock the detachable tapered sleeves in predetermined position. Another nut 57, threaded into nut 56, bears against sleeve 55 to retain said sleeve in position against electrode flange 40.

Referring to Fig. 2, a system for tuning the cavity resonator is associated with the above described assembly and disposed at right angles to the axis of wave guide 6. This system comprises two symmetrical units generally indicated by 59 and 60. Referring to the unit 60, a circular opening is provided in the narrow side of guide 6 in aligned relation with circular opening 33 in the tube-mounting assembly. An internally threaded sleeve 61 is associated with the guide side at the circular opening, a reduced section 62 thereof extending into the guide and bearing against the aligned portion of sleeve 17. An adjusting nut 63, threaded into sleeve 61, carries at its reduced end 64, a plunger 65. Plunger 65 is adjustable to accurately tune the resonator. Detailed description of symmetrical unit 59 is unnecessary, it being sufficient to say that tuning is best accomplished by adjusting both units.

The above described assembly provides for easy removal and replacement of gas discharge tube 35. This readily is accomplished by first removing nuts 57 and 56, respectively, at which time sleeve 55 will drop out to free the lower tube electrode. Next, the remaining assembly within tapered sleeve 17 may be removed from the sleeve. Nut 50 releases retaining sleeve 45, which is removed by expanding sleeve 25 to permit disengagement of the aligning pin 46. Sleeve 25 may be further expanded to permit removal and replacement of the tube. Reassembly is easily accomplished by reversing the above procedure.

The tapered surfaces of the two sleeves cooperate to position the tube properly within guide 6, the bearing surfaces therebetween providing a firm, electrical contact between the tube and the guide.

Having thus described the invention, what I claim as new and desire to secure by Letters Patent is:

1. A holder for a breakdown type of gas discharge tube, said holder comprising a metal body having a transverse channel therethrough forming a portion of a wave guide, said body having an elongated channel longitudinally thereof and perpendicular to said wave guide channel, said longitudinal channel being receptive to a removable and replaceable gas discharge tube, said body being separable into two parts lengthwise thereof, said two parts having means including tapering and apertured telescoping portions for assembling said two parts with the tube clamped in accurately predetermined position in the transverse channel.

2. A hollow wave guide, and means for detachably holding a breakdown type gas discharge tube in position in said hollow wave guide, said means including a hollow metallic body extending through said wave guide, said body being separable into two parts lengthwise thereof, the said two parts having interfitting tapering telescopic clamping portions to interfit and clamp said gas discharge tube therebetween.

3. A wave guide and a device to support a gas discharge tube transversely within said wave guide, said device comprising a first internally tapered metallic sleeve disposed transversely of

said wave guide and diametrically apertured in alignment therewith; a second metallic sleeve externally tapered and apertured complementary to said first sleeve and having flanged surfaces 5 formed integral therewith to engage said tube, said second named sleeve further being transversely split forming a pair of circumferentially expandable, resilient, tube engaging arms; a pair of metallic retaining sleeves longitudinally displaceable within said second named sleeve to press 10 said tube against said flanged surfaces; and longitudinally displaceable metallic members threadedly coupled to said second sleeve and frictionally coupled to said retaining sleeves to position said 15 second named sleeve, said retaining sleeves and said tube within said first named sleeve.
